UNITED STATES PATENT OFFICE

GEORGE W. BLAKESLEY, OF KANSAS CITY, MISSOURI

GAS BURNER

Application filed August 16, 1929. Serial No. 386,470.

My invention relates to gas burners, and more particularly to gas burners having means responsive to changes in temperature for controlling flow of gas, the principal objects of the invention being to control flow of air through a burner coincidentally with the control of gas.

The invention is particularly applicable to a gas burner having a pilot light and adapted for use in a domestic furnace, and in a situation where a draft of air may flow through the ash pit and fire bowl, and therefore has for a further object to set up and suspend flow of air through the fire bowl synchronously with setting up and suspending flow of gas to the burner, whereby air may be available for promoting combustion of gas in the fire bowl and moving products of combustion, and the flow of air will be cut off when the fuel supply is cut off to prevent extinction of the pilot light.

In accomplishing these and other objects of the invention, I have provided improved details of structure, the preferred forms of which are illustrated in the accompanying drawings, wherein:

Fig. 1 is a vertical central section from front to back through the lower portion of a furnace equipped with my improved burner and draft control mechanism.

Fig. 2 is a fragmentary perspective view of the draft control mechanism, a housing wall being partly broken away to show the position of a fuel mixture conduit.

Fig. 3 is a plan view of the burner and control mechanism, sections of the burner and a cover for the control mechanism being removed, and the upper housing wall being broken away for better illustration of details of construction.

Fig. 4 is a section on the line 4—4, Fig. 3.

Fig. 5 is a section on the line 5—5, Fig. 4.

Fig. 6 is a vertical transverse section of the center of the burner, one fuel inlet nipple

being removed and the other partly broken away.

Referring in detail to the drawings:

1 designates a furnace including a fire bowl 2 having vertical walls 3 forming a chamber 4, an ash pit 5 having a door opening 6, and an annular flange 7 around an opening 8 affording communication between the fire bowl chamber and the ash pit.

Mounted in the ash pit with its outer end projecting from the ash pit door is a housing 9 later described, through which an air draft inlet conduit 10, fuel mixture pipes 11 and 12, and a pilot light tube 13 extend toward the fire bowl.

Mounted on the upwardly turned inner end 14 of the air conduit 10 is an annular base or header comprising a pair of mated similar semi-circular castings 15 and 16 having concave web portions 17 provided with flanges 18 adapted to engage the conduit and form an axial opening in the base registering with the end of the conduit when the base members are mounted thereon. Vertical ears 19 on the webs are adapted to receive bolts 20 for securing the base members together.

The base members have hollow peripheral portions forming chambers 21, and each has a gas inlet opening 22 into which the inner ends of corresponding fuel pipes 11 and 12 are connected. Each base member has a plurality of nipples or nozzles 23 formed in upwardly projecting bosses 24 arranged in rings adjacent its outer edge and communicating with the chamber 21.

A cover member 25 mounted on each base member has openings 26 registering with the nozzles 23 and an arcuate groove 27 to receive deflecting members 28 presently described. The covers have depending peripherally flaring flanges 29 shaped to form shoulders for engaging shouldered outer edge portions of the base members, whereby the covers are supported in spaced relation with the nozzle bosses for admitting air to the

streams of fuel passing from the chambers 21 to the openings of the covers.

The cover members are adapted to fit together closely to form a sealing top for the bowl-like base. Ears or flanges 30 on the inner edge of the cover member may interlockingly engage adjacent edges of the other member for effecting the connection thereof.

The deflecting members 28 comprise narrow slabs of refractory material mounted on end in the grooves 27 in inclined position and in edge abutting relation to form a closed bowl-like frusto-conical deflector adapted to deflect gases moving from the base openings 15 toward the fire bowl walls.

The inclination of the deflecting members is preferably conferred by forming the grooved portions of the covers with radially inclined groove floors, and the central portions of the covers are depressed to form a concave closed bottom for the bowl-like deflector when the covers are connected.

The deflecting members 28 are preferably assembled in sections, for example four equal sections each comprising a number of members attached to an upstanding outer edge flange 31 of a quadrant sector plate 32 by bolts 33. The sectors 32 are provided with perforate ears 34 on inner edges to receive bolts for securing the several sections together and forming a partition in the deflector intermediate the upper and lower ends thereof.

The upper end of the deflector preferably extends in slightly spaced relation with the walls of the fire bowl to form the reduced annular outlet end of an annular upwardly contracted chamber or channel 35 for gases moving from the base toward the smoke outlet of the furnace.

Sealing means 36, for example a body of asbestos is installed on the flange 7 between the periphery of the base and the fire bowl to prevent entrance of air to the channel 35 otherwise than through the openings of the cover members.

The apparatus further includes a constantly burning pilot burner or light 37 in the channel 35 fed through the tube 13 extending into and through the housing.

An apertured partition 39 in the housing defines an open-top housing chamber 40 exterior to the furnace, having a front or end wall 41 provided with draft inlet openings 42. The pilot burner tube 13 extends through an aperture 43 in the partition and is connected by a valved fitting 44 to a tube 45 leading from the gas supply line and supplied with gas under relatively constant pressure.

The fuel mixture pipes 11 and 12 have flaring outer ends 46 abutting the inner face of the partition around air ports 47 therein, and forming funnel-like mixing chambers 48. Nipples 49 mounted on the partition in a cen-

tral position with reference to the ports support air control valves or disks 50 sleeved thereon and receive the inner ends of valved fittings 51 having outer ends communicating with a header 52 connected with an automatically controlled valve 53 in the gas supply line. Valves 54 in the fittings are manually operable for adjusting the flow of gas to the mixing chambers 48.

The outer end of the air conduit 10 is mounted at a relatively large central opening 55 in the partition for communication with the housing chamber 40 for delivering a draft between the upper surface of the hollow base portions and the cover members to the gases moving from the nozzles toward and through the openings of the cover members.

A damper 56 for controlling the draft is pivotally supported at the outer end of the air conduit by a shaft 57 mounted in ears 58 projecting from the partition. A crank arm 59 on the shaft is operable through a link 60 by regulating apparatus generally designated 61.

The link 60 has one end pivoted in the housing wall and is provided with a slot in its opposite end in which a laterally bent end of the crank arm 59 is slidably retained. Force is applied as later described to an intermediate portion of the link for lifting the damper.

The regulating device may include a housing 62, and may be electrically operated, as indicated by switch contact posts 63 projecting from the housing, and in accordance with well known practice to control the valve 53 for setting up and suspending flow of gas toward the burner.

I combine with the gas-controlling feature of the device, means for synchronously controlling the movement of air through the conduit 10, including a lever arm 64 having one end pivotally mounted in ears 65 of a base 66 secured to the upper face of the housing 62, adjacent the outer edge thereof, and connected with the link 60 through an adjustable link 68. The arm is vertically pivotal in a path above the shaft 67 normally present in regulating devices of the type shown for operating the valve 53. The shaft moving upwardly for opening the valve 53 encounters the arm 64 and lifts the same, thus effecting opening pivotal movement of the damper to permit air to move through the conduit 10.

The damper is provided with a weight 69 tending to move the damper to closing position. When the shaft 67 moves downwardly for closing the valve 53, the damper is permitted to move toward conduit-closing position and retracts the arm 64 for retarding the same in position to be lifted by the shaft.

The housing 9 further preferably comprises an inner portion extending in the ash pit with its outer end engaged in the ash pit door opening, and an outer portion in-

cluding side walls 70 provided with vertical edge flanges 71, a bottom 72 having peripheral flanges 73, and a cover member 74 having flanges 75. The partition comprises a plate 5 provided with inwardly projecting horizontal flanges 76 adapted to engage the inner face of the outer end of the inner housing portion and spaced from the edges of the plate to leave keeper-like stop portions engageable by the flanges of the cover and bottom.

The partition plate further has offset vertical edge portions 77 forming grooves to receive the inner vertical flanges 71 of the side walls. The end wall 41 also comprises a plate similar to the partition, having offset vertical edge portions 78 adapted to receive the outer vertical edge flanges of the side walls.

The partition and end wall 41 may have slotted ears 79 to receive fastening means for securing the cover to the housing. The cover preferably has an opening 80 for access to the manually operable valves, and a door 81 may be mounted over the opening and attached to the cover for preventing unauthorized access to the housing.

The regulating apparatus may include a handle 82 for manually opening and closing the valve 53.

The housing construction described is particularly adapted for forming the inner housing portion of relatively light weight material, for example sheet metal, and forming the outer housing portion and partition of cast plates which may be easily assembled to 35 enclose the valves and fittings illustrated. The outer housing portion is therefore relatively sturdy, and provides protection to the valves and damper against accidental damage and molestation.

40 In using apparatus constructed as described, the pilot flame is constantly operating to ignite gas delivered to the channel 35. When a gas mixture is being delivered to the channel, the fire bowl and deflector are heated, and a draft or stream of air flows through the outer housing portion, conduit 10, and cover openings into the channel and outwardly from the furnace.

When flow of fuel mixture is suspended 50 the heated fire bowl tends to sustain the flow of air which if permitted to continue would tend to extinguish the pilot flame and cool the fire bowl and deflector.

The damper 56 however is held in open position by the device which controls flow of fuel, and when fuel flow is suspended the damper is released and automatically moves to draft-stopping position.

When fuel flow is set up again, by opening the valve 53, the damper-control members are synchronously operated to permit flow of air through the burner and fire bowl.

What I claim and desire to secure by Letters Patent is:

45 1. In apparatus of the character described,

including a fuel mixture conduit, a secondary air supply conduit, and valves controlling flow of fuel mixture and air through said conduits, a housing including an apertured plate engaging the outer ends of said conduits, said housing enclosing the valves and including removable side walls and a perforate end wall.

2. In apparatus of the character described, a furnace including an ash pit having a door opening, a burner, a fuel conduit, an air conduit, valves for controlling flow of fuel and air through said conduits, a housing mounted in the ash pit and adapted for extending said conduits therethrough, the outer end of 75 the housing registering with the ash pit door opening, an apertured plate closing said opening and supporting said conduits, and a second housing enclosing said valves and including said plate.

3. In a gas burner having fuel and air inlet conduits, a housing adjacent the inlet ends of said conduits, a damper controlling movement of air through the air inlet conduit, a crank for operating the damper, a link pivotally mounted on the housing having a slot to receive said crank, a second link having pivotal connection with said first named link, and means controlling flow of fuel through said fuel inlet conduit having 90 means for operating said second named link to effect operation of the damper.

4. In a gas burner having a door opening, a plurality of conduits having outer ends located in said opening, a plate closing said opening and having apertures to receive said outer ends of the conduits, a housing including side walls removably engaged with said plate and an end wall removably engaged with said side walls and having apertures 100 for inlet of air to the housing, and means including valves located in the housing for controlling movement of fluids to said conduits.

5. In apparatus of the character described, 110 a burner, air and gas conduits connected with the burner, a tubular housing enclosing said conduits, a partition in the housing supporting the ends of said conduits and forming an air chamber at the end of said housing, 115 an apertured plate closing the end of the housing, a valve in the housing closing the air conduit, automatically operable means associated with the housing for controlling flow of gas through the gas conduit, and means interconnecting said air valve with said gas control means arranged to shut off the air supply from said air chamber when the gas control means operates to shut off flow of gas through the gas conduits.

6. In apparatus of the character described, a burner, air and gas conduits connected with the burner, a tubular housing enclosing said conduits, a partition in the housing supporting the ends of said conduits and forming an 120

air chamber at the end of said housing, an apertured plate associated with the air chamber portion of the housing, a valve in the housing closing the air conduit, automatically operable means associated with the housing for controlling flow of gas through the gas conduit, and means interconnecting said air valve with said gas control means arranged to shut off the air supply from said air chamber when the gas control means operates to shut off flow of gas through the gas conduits.

In testimony whereof I affix my signature.
